UNITED STATES PATENT OFFICE.

JOHN M. C. JONES, OF ONARGA, ILLINOIS.

CUTTER FOR GREEN-CORN-CUTTING MACHINES.

1,118,133.

Specification of Letters Patent.

Patented Nov. 24, 1914.

Application filed October 16, 1913. Serial No. 795,402.

To all whom it may concern:

Be it known that I, JOHN M. C. JONES, a citizen of the United States, residing at Onarga, in the county of Iroquois, in the 5 State of Illinois, have invented certain new and useful Improvements in Cutters for Green-Corn-Cutting Machines, of which the following is a specification, reference being had to the accompanying drawings.

10 This invention relates to cutting devices for green corn cutting machines, and has for one of its principal objects the provision of cutting devices capable of adjusting themselves to work upon ears of different 15 sizes.

Heretofore it has been customary to use two oppositely disposed curved blades between which the ear of corn has been forced, passing thence to two oppositely disposed 20 curved blades positioned at approximately right angles to said first-mentioned blades. It has been found that cutting devices of this type will do clean work only upon cobs of approximately the diameter of the 25 normal opening between the blades.

By my invention I have provided a construction of cutting device which will do clean work whatever the size of the ear of corn, this being accomplished by the use of 30 straight blades as hereinafter described in place of the curved blades heretofore used.

By the use of straight blades arranged in accordance with my invention I am enabled to place the spur rollers, by which 35 the ear is forced forward, closer to the blades thus securing a better and more positive feeding of the ears.

Another advantage resulting from the use 40 of my improved construction is the greater ease with which the blades can be sharpened.

It is another object of my invention to provide a construction in which the cutting blades are readily removable from the machine for repairing, sharpening or cleaning 45 the blades.

It is another object of my invention to improve devices of this general type in sundry details hereinafter pointed out.

The means by which I have accomplished 50 my objects are illustrated in the drawings and are hereinafter specifically described.

That which I believe to be new is set forth in the claims.

In the drawings,—Figure 1 is a side view 55 of one of the removable brackets supporting one pair of oppositely-disposed blades

in operative position, the spur rollers which would be used adjacent to such blades being shown diagrammatically in connection therewith; Fig. 2 is an enlarged detail, being substantially a cross section on line 2—2 of Fig. 1; Fig. 3 is a top view of the bracket shown in Fig. 1 with the cutting blades removed therefrom; Fig. 4 is a view of the bracket of Fig. 1 with one of the blades removed therefrom; Fig. 5 is a view of the blade removed from the bracket of Fig. 4; Fig. 6 is a view of the complete cutting system showing four pairs of cutting blades in operative position relative to each other, 60 the spur rollers which would normally be used in connection with such cutting system being omitted for the sake of clearness of illustration; and Fig. 7 is a modification showing the mounting of two pairs of blades 65 upon a single bracket instead of upon two brackets as shown in Fig. 6.

Referring to Figs. 1 to 6, in which corresponding parts are indicated by the same reference characters,—10 indicates a bar extending longitudinally of a green corn cutting machine, and 11 indicates a plate at a convenient distance from the bar 10 and extending parallel therewith. My improved cutting device is designed for use preferably 80 with a green corn cutting machine of the type shown in United States Patent, No. 1,037,014, issued to me on August 27, 1912. It will be understood that my improved cutting devices of the type herein shown are 85 to be substituted for the blades 82—99 and 122—123 of the patented machine, such patented machine being changed as necessary to adapt it to the use of my improved devices as will be readily understood. The 90 bar 10 and plate 11 for supporting my improved cutting devices will be suitably positioned in the patented machine parallel to the present position of the plates 112—113 of such machine.

Referring particularly to Fig. 1, 12 indicates a bracket provided with a socket 13 at one end adapted to have a working fit upon the bar 10 so as to be readily removable therefrom. The opposite end of said 105 bracket 12 is cut away at its central portion forming ears 14—15 which fit between guides 16—17 and on opposite sides of a longitudinally-extending rib 18 formed upon one face of the plate 11. It will be 110 understood that the bracket 12 is thus rendered easily removable from the machine

by merely lifting the left hand end of such bracket from the bar 10 whereupon the bracket is capable of being moved longitudinally of itself out of engagement with 5 the plate 11.

As best shown in Fig. 3 the bracket 12 is provided near one end with a boss 19 and two studs 20-21. Upon the studs 20-21 are revolvably mounted arms 22-23, respectively, being held in position on said studs by means of a plate 24 which is pivotally mounted upon the boss 19 by means of a screw 25.

As best shown in Fig. 4 when the screw 15 25 has been loosened and the plate 24 has been turned to the left the arm 23 can be lifted readily off of the stud 21, and it will be understood that when the plate 24 is turned to the right in said Fig. 4 the arm 20 22 can likewise be readily lifted from the stud 20.

Each of the arms 22-23 is provided with a set-screw 26 adapted to be adjusted relative to the boss 19 to regulate the movement of the arms 22-23 toward each other. 25 27 indicates a coiled spring mounted at its ends upon the arms 22-23 tending to hold said arms against movement away from each other. 28-29 (see Figs. 1 and 2) are knife 30 blades secured by screws or in any other suitable manner to the arms 22-23, respectively. 30-31 indicate guides adjustably mounted upon the arms 22-23 alongside the knife blades 28-29, respectively, said guides 35 extending forward and outward from the cutting edges of said blades, as best shown in Fig. 2, said guides by reason of contact with the ear as it is fed through the machine serving to move the knife blades apart 40 into proper position for cutting the kernels from the cob whatever may be the size of the ear, the guides 30-31 being adjusted relative to the blades in accordance with the size of the kernels of the corn being treated. 45 32-32^b indicate spur rollers revolvably mounted slightly in front of the blades 28-29 but directly adjacent thereto, said spur rollers being oppositely disposed and driven in any suitable manner for feeding 50 the ears between the blades as will be readily understood.

Referring now particularly to Fig. 6, which shows the complete system of cutting blades as I prefer to embody them, 33, 34 55 and 35 indicates additional brackets mounted upon the bar 10 and the plate 11 in the same manner as is the bracket 12 mounted thereon. The bracket 33 has mounted upon it arms 36-37 in the same manner as are the 60 arms 22-23 mounted upon the bracket 12, being yieldingly held together in normal position by a spring 38. 39-40 indicate the guides adjustably mounted upon said arms 36-37, and 41-42 indicate the blades 65 mounted upon said arms in horizontal posi-

tion. The bracket 34 in turn is likewise provided with arms 43-44 connected by a coiled spring 45. Said arms are provided with guides 46-47, respectively, located alongside of the diagonally positioned 70 blades 48-49, such blades being approximately at right angles to the blades 28-29 mounted upon the arms 22-23. The bracket 35 in turn is likewise provided with arms 50-51 connected by a spring 52. Said arms 50-51 are provided with guides 53-54, adjustably mounted thereon alongside of blades 55-56, respectively, said last-named blades being mounted in vertical position.

57 indicates spacing blocks mounted upon the bar 10 for properly spacing the brackets 12-33-34-35 upon said bar 10.

From the above description and from a reference to Fig. 6 it will be seen that the cutting portions of the several pairs of oppositely-disposed blades lie on opposite sides of a longitudinally-extending line passing through the point marked A in said figure. It will be understood that an ear of corn will be fed to the blades along the line indicated by A, being forced into contact with the respective blades by suitable pairs of spur rollers similar to the rollers 32-32^b driven in opposite directions by any suitable means, a pair of such rollers being 95 located between each two adjacent pairs of cutting blades. It will be understood that as the ear approaches a pair of blades the ear first engages the guides extending in advance of the blades, serving to separate the knives the required amount against the action of the spring by which said knives are held yieldingly together. I have found in practice that by the use of my improved construction the corn is cut evenly all 100 around to much greater advantage than can be done by the use of curved blades.

In Fig. 7, which shows a modified construction, I have indicated the corresponding parts by the same reference numerals, 110 but with the addition of an exponent a. In this figure, 58 indicates a bracket mounted upon the bar 10^a and the plate 11^a just as are the brackets heretofore described. 59-60 indicate arms mounted upon the 115 bracket 58 just as the arms 22-23 are mounted upon the bracket 12, said arms 59-60 being yieldingly held together by a spring 61. 62-63 indicate guides adjustably mounted upon the arms 59-60, respectively, and 64-65 indicate the cutting blades mounted upon said arms. 66-67 indicate a second pair of arms likewise mounted upon the bracket 58 and held yieldingly together by means of the spring 68. 69-70 indicate guides adjustably mounted upon said arms 66-67, respectively, and 71-72 indicate cutting blades mounted upon said arms adjacent to said guides. It will be understood that the bracket 58 may be substituted for the 120 125 130 135 140 145 150 155 160 165 170 175 180 185 190 195 200 205 210 215 220 225 230 235 240 245 250 255 260 265 270 275 280 brackets 12 and 31 in a machine adapted for its use. It will likewise be understood that another single bracket may be substituted for the brackets 33-35 if desired, the ultimate effect of the modified construction being substantially the same as that shown in Fig. 6 except that in the use of the modified construction it would not be possible to remove from the machine a single pair of the blade-
5 carrying arms. Moreover in the modified form of construction only a single pair of spur rollers would be used with each two pairs of cutting blades instead of a pair of such rollers with each pair of cutting blades.

15

What I claim as my invention and desire to secure by Letters Patent, is—

1. A cutter for green corn cutting machines, comprising a pair of oppositely-disposed blades, a second pair of oppositely-disposed blades positioned substantially at right angles to said first-mentioned pair, a third pair of oppositely-disposed blades positioned at an angle of substantially forty-
20 five degrees relative to said before-mentioned pairs, and a fourth pair of oppositely-disposed blades positioned substantially at right angles to said third pair, the blades of each of said pairs having their
25 cutting portions on opposite sides of a common line whereby an ear of corn is adapted to be passed between said blades and be cut evenly all around, said ear being passed between the blades of each of said pairs.
30
35

2. The combination of a pair of oppositely-disposed blades having substantially straight cutting portions movable toward and from each other, and means located in advance of said blades immediately adjacent thereto for feeding an ear of corn between said blades, said feeding means comprising a pair of oppositely-disposed spur rollers rotatable upon parallel axes extending transversely of said blades.
40
45

3. The combination of a pair of oppositely-disposed blades having substantially straight cutting portions, guides mounted adjacent to the cutting edges of said blades and extending in advance thereof, and a pair of oppositely-disposed spur rollers rotatably mounted at substantially right angles to said blades, said rollers extending substantially to the cutting edges of said blades and one of said rollers extending between said guides.
50
55

4. The combination of a pair of oppositely-disposed blades having substantially straight cutting portions, guides mounted

adjacent to the cutting edges of said blades and extending in advance thereof, and a pair of oppositely-disposed spur rollers rotatably mounted at substantially right angles to said blades, said rollers extending substantially to the cutting edges of said blades and one of said rollers extending between said guides, said guides being adjustable laterally relative to said blades toward and away from said last-mentioned spur roller.
60
65

5. In a cutting device for green corn cutting machines, the combination of a bracket, means for removably supporting said bracket, and a pair of oppositely-disposed cutting blades pivotally mounted on said bracket and adapted to have an ear of corn forced between them.
70
75

6. In a cutting device for green corn cutting machines, the combination of a bracket, a pair of studs thereon, a pair of arms removably mounted on said studs and adapted to swing thereon, a pair of cutting blades mounted on said arms, and a pivotally-mounted plate for holding said arms against withdrawal from said studs.
80
85

7. In a cutting device for green corn cutting machines, the combination of a bracket, a pair of studs thereon, a pair of arms removably mounted on said studs and adapted to swing thereon, a pair of cutting blades mounted on said arms, yielding means tending to hold said blades against swinging away from each other, a boss on said bracket adjacent to said studs, and a plate pivotally mounted on said boss adapted to hold said arms against withdrawal from said studs.
90
95

8. In a cutting device for green corn cutting machines, the combination of a bracket, a pair of studs thereon, a pair of arms removably mounted on said studs and adapted to swing thereon, a pair of cutting blades mounted on said arms, yielding means tending to hold said blades against swinging away from each other, a boss on said bracket adjacent to said studs between said arms, a plate pivotally mounted on said boss adapted to hold said arms against withdrawal from said studs, and adjustable means carried by said arms adapted to contact said boss for regulating the distance at which said cutting blades are held from each other.
